UNITED STATES PATENT OFFICE.

JAMES A. KAMMERDINER, OF LOS ANGELES, CALIFORNIA.

ROTARY JAR.

Application filed November 29, 1926. Serial No. 151,325.

This invention relates to a rotary jar for use in well drilling apparatus, and more particularly to a jar which may be placed in a string of drill pipe, to remain there during the drilling operations. It is thus available for immediate use when the need arises. This is of very great value, as it is well known to those skilled in the art that if, upon a tool becoming stuck in the hole, means are instantly at hand to loosen it, it can, in the majority of cases, be easily dislodged. But if it is necessary to come out of the hole with the drill pipe (leaving the tool behind,) attach suitable fishing tools and run in again, much valuable time is wasted, and the lost tool has had a chance to become more firmly lodged in the hole, increasing the difficulty of its removal.

It is accordingly an object of this invention to provide a rotary jar which may be used in a string of drill pipe during drilling operations. A further object is to provide a jar which may be readily manufactured. Tools of this type as heretofore constructed have been subject to rapid wear and it is a still further object of this invention to provide a jar of increased durability and wearing qualities.

These objects together with other objects and corresponding accomplishments are obtained by means of the embodiment of my invention illustrated in the accompanying drawing in which:

Fig. 1 is an axial section through a jar in its normal, or set, position; Fig. 2 is a similar section through a portion of the shell only; Fig. 3 is a section corresponding to Fig. 1 and taken at right angles to it, the lower portion being broken away; and Figs. 4 and 5 are sections as seen on the correspondingly numbered lines of Fig. 1 looking in the direction indicated by the arrows.

Referring more particularly to the drawing, a cylindrical body or shell 6 is provided with a tapered, threaded pin 7 at its upper end and having a bore 8 extending through it. The diameter of the upper portion of the bore is reduced to form a plunger chamber 9 and is still further reduced where it passes through the pin. The body is internally threaded at its lower end and mounted therein is a closure member 10, forming an anvil. Within the bore is a mutilated thread 11, formed of two diametrically opposed portions, each occupying ap-

proximately one quarter of the periphery. Below these threads are two keys or abutments 12, also diametrically opposite each other and extending from one edge of the thread to the center, thus occupying approximately one eighth of the periphery each, and leaving three-eighths of it unoccupied between them.

Disposed within the shell is a hammer comprising a cylindrical head 15 adapted to engage the anvil 9 and a tubular mandrel 16 extending slidably through the bore in the anvil. The lower portion of the mandrel terminates in a tapered threaded pin 17 to which any suitable tool may be attached, in this case a bit or under reamer. The mandrel 16, above the hammer 15 is provided with two diametrically opposite keys or abutments 18 each occupying approximately one-eighth of the periphery of the mandrel and leaving three-eighths clear between them. Above these again are mutilated threads 19, diametrically opposite and occupying approximately one-quarter of the periphery, for engagement with the corresponding threads in the shell. Above threads 19 are bosses 20, of such length and position that they will keep threads 19 from engaging threads 11 until the tool is entirely collapsed and the full number of threads can engage each other. The upper portion of mandrel 16 is reduced in diameter to form a plunger 21, provided with packing 22, which works in chamber 9.

It will be noted that there is sufficient clear space between the thread sections 11 for the thread sections 19 to pass and vice versa. Also the keys 12 and 18 form a spline and are so proportioned as to permit only a quarter turn of the shell relative to the mandrel; in one extremity of this movement, the threaded sections are fully engaged, while at the other they are free and vertical movement of the shell relative to the mandrel can occur. However, the spline acts to limit rotary movement at all portions of the mandrel.

The hammer member is provided with a bore 23, extending therethrough, so that circulation may be maintained from the drill pipe above, through the jar and on through the tool or pipe attached to pin 17. The packing 22 forms a tight seal between plunger 21 and plunger chamber 9, whatever the position of the hammer, and prevents

loss of circulation into the cage and thence between members 10 and 16 into the hole. Mounted in closure member 10 and secured thereto by a set screw 24 is one end of a compression spring 25 which encircles the lower portion of mandrel 16; the other end rests in a recess in the collar above pin 17. This spring must be wound to correspond with the mutilated threads 11 and 19, that is, if the threads are left hand, the spring must be wound left hand and vice versa.

The jar is placed in a string of drill pipe, the drilling tools at the lower end, and these are then set on the bottom. The weight of pipe above the jar will cause it to telescope and compress spring 25, which tends to unwind and cause rotation of the cage and mandrel relative to each other. This is prevented however by lug 20, until the threads are fully engaged, and the jar is fully telescoped. When this occurs, cage 6, being supported by the drill pipe which is free to turn, will be turned one quarter of a revolution by spring 25 acting against the mandrel, which is held stationary by the drilling tools on bottom. This will bring the threads into full engagement as clearly shown in Fig. 4 of the drawing and lugs 12 and 18 together, as shown in Fig. 5. Further movement is obviously prevented by these lugs. The tool is now set; the drill is picked up off bottom and drilling proceeds, the twist of the drill pipe being transmitted from shell 6 by lugs 12 and 18 which comprises a rotary coupling to mandrel 16 and the drill. It is evident that these lugs may be of any length to obtain the required strength. Should the drill become stuck, the drill pipe is lifted and a pull exerted on the tools, which may be sufficient in itself to free them. If not, the tension in the drill pipe caused thereby will stretch it, as a long string of such pipe has considerable elasticity. When sufficient tension has been attained, the pipe is given a reverse quarter turn, which causes the thread sections 11 to slip out of engagement with thread sections 19 into the clear space between them, permitting the shell to ride up on the hammer member until the anvil strikes the hammer head. This will give a heavy blow in an upward direction to the drilling tools and probably free them. If the first blow fails, as many blows as desired may be struck, by repeating the operations of setting the jar and stretching the pipe just described. When free the tools may be removed from the hole, or the jar reset and drilling proceeded with as desired. The jar can be used for a plain fishing job, in a similar manner, in which case it is run in the hole with suitable fishing tools attached to its lower end. When a hold is secured on the "fish", the jar is set and blows delivered as before described.

What I claim is:

1. A rotary jar for use in well drilling comprising a rotary hammer member and a rotary anvil member telescopically connected, each of the members having trip shoulders, said shoulders being interrupted to permit the passage in an axial direction of the shoulders on the hammer member past the shoulders on the anvil member whereby when said shoulders are in engagement further longitudinal movement of the members is prevented, but when out of engagement longitudinal movement of said members is permitted, and spline means for said members permitting a limited rotary movement for engagement and disengagement of said shoulders.

2. A rotary jar for use in well drilling comprising a rotary hammer member and a rotary anvil member telescopically connected, each of the members having trip shoulders, said shoulders being interrupted to permit the passage of the shoulders on the hammer member past the shoulders on the anvil member whereby when said shoulders are in engagement further longitudinal movement of the members is prevented, but when out of engagement longitudinal movement of said members is permitted, and a spline rotary coupling for said member permitting a limited rotary movement for engagement and disengagement of said shoulders.

3. A rotary jar for use in well drilling comprising a rotary hammer member and a rotary anvil member telescopically connected, each of the members having trip shoulders, said shoulders being interrupted to permit the passage in an axial direction of the shoulders on the hammer member past the shoulders on the anvil member whereby when said shoulders are in engagement further longitudinal movement of the members is prevented, but when out of engagement longitudinal movement of said members is permitted, and spline means independent of said shoulders for transmitting rotary motion from one member to the other at all axial positions of said members and permitting a limited rotary movement for engagement and disengagement of said shoulders.

4. A rotary jar for use in well drilling comprising a rotary hammer member and a rotary anvil member telescopically connected, each of the members having trip shoulders, said shoulders being interrupted to permit the passage in an axial direction of the shoulders on the hammer member past the shoulders on the anvil member whereby when said shoulders are in engagement further longitudinal movement of the members is prevented, but when out of engagement longitudinal movement of said members is permitted, means operated by closure movement of said members to turn said shoulders

into operative engagement, and spline means independent of said shoulders to limit the rotary movement between said members at all axial positions of said members and permit engagement and disengagement of said shoulders.

5. A rotary jar for use in well drilling comprising a rotary hammer member and a rotary anvil member telescopically connected, each of the members having trip shoulders, said shoulders being interrupted to permit the passage in an axial direction of the shoulders on the hammer member past the shoulders on the anvil member whereby when said shoulders are in engagement further longitudinal movement of the members is prevented, but when out of engagement longitudinal movement of said members is permitted, and spline means independent of said shoulders to limit movement between said members at all longitudinal positions engageable at all axial positions of said members and permitting a limited rotary movement for engagement and disengagement of said shoulders.

6. A rotary jar for use in well drilling comprising a rotary hammer member and a rotary anvil member telescopically connected, each of the members having trip shoulders, said shoulders being interrupted to permit the passage of the shoulders on the hammer member past the shoulders on the anvil member whereby when said shoulders are in engagement further longitudinal movement of the members is prevented, but when out of engagement longitudinal movement of said members is permitted, and means independent of said shoulders to limit the rotary movement between said members

located longitudinally beyond said shoulders and operable at all axial positions of said members.

7. A rotary jar for use in well drilling comprising a rotary hammer member and a rotary anvil member telescopically connected each of the members having correspondingly mutilated threads forming trip shoulders to permit the longitudinal passage of the shoulders in the hammer member past the shoulders on the anvil member when in one angular position and to prevent longitudinal movement of the members when the shoulders are in engagement, and spline means for said members permitting a limited rotary movement for engagement and disengagement of said shoulders.

8. A rotary jar for use in well drilling, comprising a rotary hammer member and a rotary anvil member telescopically connected, each of the members having correspondingly mutilated threads forming trip shoulders to permit the longitudinal passage of the shoulders when in one angular position and to prevent longitudinal movement of the members when the shoulders are in engagement, and abutments longitudinally spaced from said shoulders on said anvil members and on said hammer member to provide a spline permitting engagement and disengagement of said shoulders but engageable at all axial positions of said members.

In witness that I claim the foregoing I have hereunto subscribed my name this 17th day of November, 1926.

JAMES A. KAMMERDINER.
